UNITED STATES PATENT OFFICE.

NAPOLEON FLETCHER, OF FARWELL, TEXAS.

DOUBLE-CAPACITY WELL PUMP.

Application filed June 13, 1925. Serial No. 36,920.

This invention relates to double capacity well pumps, and it consists of the novel construction, combination and arrangement of parts hereinafter fully described and 5 claimed, and illustrated in the accompanying drawings, wherein:

Figure 1 is an elevational view of a double capacity well pump constructed in accordance with my invention, a portion of the 10 outer cylinder of the pump being broken away to illustrate the manner in which the space between the inner and outer cylinders is separated into lower and upper chambers.

Figure 2 is a sectional view taken on a 15 plane extending vertically and centrally through the pump.

Figure 3 is a sectional view taken on the vertical plane indicated by the line 3—3 of Figure 2,

20 Figure 4 is a detail perspective view of the partition by which the space between the inner and outer cylinders of the pump are separated into lower and upper chambers, and

25 Figure 5 is a sectional view taken on the horizontal plane indicated by the line 5—5 of Figure 2.

Corresponding and like parts are referred to in the following description, and designated in the several views of the accompanying drawings, by similar reference characters.

The pump comprises relatively spaced inner and outer cylinders 1 and 2, respectively.

35 The cylinders 1 and 2 are secured in spaced relation, and the ends of the outer cylinder 2 are closed by a bottom plug 3 and top plug 4, which have an external screw threaded connection with the inner cylinder 1 and an internal screw threaded connection with the outer cylinder 2. An intake port 5 communicating with the lower end of the inner cylinder 1 and a discharge port 6 communicating with the upper

40 end of this cylinder, are formed respectively in the bottom plug 3 and top plug 4. The inner cylinder 1 is divided into a lower chamber 7 and an upper chamber 8 by a plug 9 supported within this cylinder centrally between the ends thereof. The space

45 between the inner cylinder 1 and the outer cylinder 2 is divided into a lower compartment 10 and an upper compartment 11 by a partition which comprises horizontally disposed semi-annular members 12 and 13 and vertically disposed bars 14. The member 12

is located below the member 13, these members are connected by the strips 14, and they extend in opposite directions from said strips. The members 12 and 13 occupy positions at opposite sides of the inner cylinder 1 and have a snug fit with the opposing surfaces of this and the outer cylinder 2. The strips 14 occupy positions at opposite sides of the inner cylinder 1 and have a snug fit with the opposing surfaces of the cylinders. The partition may be secured in place by cap screws 15 or in any other suitable manner. Openings 16 formed in the inner cylinder 1 between the plug 9 and partition member 13 and at one side of the partition strips 14, establish communication between the upper end of the lower chamber 10 and the lower end of the upper chamber 8. Openings 17 formed in the inner cylinder 1 between the plug 9 and partition member 12 and at the opposite side of the partition strips 14, establish communication between the upper end of the lower chamber 7 and the lower end of the upper chamber 11. Communication between the lower ends of the chambers 7 and 10 is established by an annular series of openings 18 in the cylinder 1, and communication between the upper ends of the chambers 8 and 11 is established by an annular series of openings 19 in this cylinder.

50 A foot valve 20 is located in the lower end of the inner cylinder 1 and rests on a conical seat 21. A valved piston 22 is arranged within the cylinder 1 between the plug 9 and foot valve 20, and a similar piston 23 is arranged in this cylinder above the plug 9. The plug 9 is supported from the foot valve 20 by a rod 24 which passes through the piston 22. The pistons 22 and 23 are connected together by rods 25 which pass through the plug 9 and stuffing boxes 26 carried by said plug. An operating rod 27 is secured to the piston 23.

55 From the foregoing description, taken in connection with the accompanying drawings, it should be apparent that the pump is of the double acting type and that during the operation thereof the pistons 22 and 23 will simultaneously move in common directions. The piston 22 will during its upward movements draw water into the chamber 7 through the intake port 5 and foot valve 20 and force water from the chamber 7 into the 60 chamber 11 through the openings 17. The piston 23 will during its upward movements

draw water into the chamber 8 by way of the intake port 5, openings 18, chamber 10 and openings 16, and at the same time force water out through the discharge port 6. In view of the manner in which they are connected together and to the operating rod 28, the foot valve 20, piston 22, plug 9, and piston 23 may be simultaneously moved from the inner cylinder 1 for repair or other purposes. The pump will lift double the quantity of water of a single lift pump, it is simple and durable, and all parts thereof that are subjected to wear may be readily removed for repairs and replacements without withdrawing the cylinders from the well.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

23 What is claimed is:

1. A double capacity pump comprising spaced inner and outer cylinders, a partition separating the inner cylinder into lower and upper chambers, a partition separating the space between the cylinders into lower and upper chambers and embodying spaced semi-annular members horizontally disposed and located at opposite sides of the inner cylinder and vertically disposed strips connecting said members, said inner cylinder being provided with openings adjacent its ends and with openings located between the partition of the inner cylinder and the horizontal partition members, a foot valve in the lower end of the inner cylinder, a valved piston in each chamber of the inner cylinder, and operating and connecting means for the pistons.

2. A double capacity pump comprising an inner cylinder, a foot valve within the cylinder, a partition within the cylinder, a rod supporting the partition from the foot valve, a piston within the cylinder below the partition, a piston within the cylinder above the partition, rods connected to the pistons and passing through the partition, an operating rod connected to the upper piston, a lower chamber communicating with the cylinder above and below the partition, and an

upper chamber communicating with the cylinder above and below the partition.

3. A double capacity pump comprising spaced inner and outer cylinders, a partition separating the inner cylinder into lower and upper chambers, a second partition inserted between the cylinders to divide the intermediate space into lower and upper chambers, said second partition embodying vertically spaced semi-annular members horizontally disposed and located above and below the first partition at opposite sides of the inner cylinder, said second partition also embodying vertically disposed strips connecting said members and located at other opposite sides of the inner cylinder, means 70 securing the second partition to the outer cylinder, said inner cylinder being provided with openings adjacent its ends and with openings located between the first partition and the horizontal members of the second partition, a foot valve in the lower end of the inner cylinder, a valved piston in each chamber of the inner cylinder, and operating and connecting means for the pistons.

4. A double capacity pump comprising spaced inner and outer cylinders, a partition separating the inner cylinder into lower and upper chambers, a second partition inserted between the cylinders to divide the intermediate space into lower and upper chambers, said second partition embodying vertically spaced semi-annular members horizontally disposed and located above and below the first partition at opposite sides of the inner cylinder, said second partition also embodying vertically disposed strips connecting said members and located at other opposite sides of the inner cylinder, means 90 securing the second partition to the outer cylinder, said inner cylinder being provided with openings adjacent its ends and with openings located between the first partition and the horizontal members of the second partition, a foot valve in the lower end of the inner cylinder, a rod supporting the first partition from the foot valve, a valved piston in each chamber of the inner cylinder, rods connecting the pistons and passing through the first partition, and piston operating means.

In testimony whereof I affix my signature.

NAPOLEON FLETCHER.
